UNITED STATES PATENT OFFICE.

EMILE AUGUSTIN BARBET, OF PARIS, FRANCE, ASSIGNOR TO SOCIÉTÉ E. BARBET & FILS & CIE., OF PARIS, FRANCE.

RECTIFYING PROCESS AND APPARATUS.

1,292,676.

Specification of Letters Patent. Patented Jan. 28, 1919.

Application filed March 6, 1914. Serial No. 822,953.

To all whom it may concern:

Be it known that I, EMILE AUGUSTIN BARBET, a citizen of the French République, residing at 5 Rue de L'Echelle, Paris, in the Republic of France, have invented certain new and useful Improvements in Rectifying Process and Apparatus, of which the following is a specification.

The present invention relates to an improved method of obtaining alcohol from fermented liquids containing the same, such as wine or from alcohol containing distillates at will, and to an apparatus for use in connection with said method, said method and apparatus operating with a maximum economy of steam and producing completely purified alcohols from fermented musts.

In the accompanying drawing, Figures 1 and 1^a, show a side elevation of a complete apparatus for carrying out my improved process in which the interior construction of certain parts is shown diagrammatically.

Fig. 2 shows the apparatus of Figs. 1 and 1^a in the arrangement used for operating on phlegms, as subsequently described, parts not operating being eliminated for the sake of clearness.

Fig. 3 is a vertical section, and

Fig. 4 is a plan view of a differential steam regulator, which may be employed in connection with the apparatus shown in Figs. 1 and 2.

Referring to Figs. 1, 1^a and 2, the wine to be treated is first heated in a heat exchanger *a*, which it enters through pipe *a*³ by the waste heat from the exhausting column *m*, which enters through pipe *a*⁷ and leaves through pipe *a*⁶ and then passes by pipe *b*, provided with a valve *b*¹ into the upper part 35 of the preliminary distilling column *c*. Steam is admitted by opening the valve *e*² into the bottom of the column *c*. The vapor generator both by the preheating in *a* and the heating in *c*, which liberates the products more volatile than alcohol together 40 with a small amount of the alcohol, then passes by pipe *e* into the first rectifier *F*, containing cooled plates *f*, and uncooled plates *g*. The vaporous products not condensed by the cooled plates *f*, pass through pipe *i*² to a condenser *i* in which they are condensed and the condensate is returned 45 through pipe *i*¹ to the upper part of the first rectifier, the condensed forerunnings being extracted at a test gage. The plates *f* are

5 maintained at a regulated temperature, by means of a cooling fluid circulating between these plates and the refrigerator *h*, flowing to the cooled plates through pipe *h*⁴ and returning through pipe *h*⁵. If desired the condenser *i* may be omitted, if sufficient cooling is effected by the cooling plates *f*. The lower portion of the rectifier is heated by means of steam introduced through valve *h*² and pipe *h*³ and controlled by the differential regulator *j*¹. The liquid condensed by the plates *f* flows downwardly through the column and out through the pipe *n* to the main rectifying column to be described further on. The liquid from the bottom of the column *c*, which still contains the greater portion of the alcohol, passes by pipe *l*, into the upper part of the exhausting column *m*, steam being admitted to the bottom of this column by the pipe *c*', the vapor from the top of the column passing through the pipe *p*, into the main rectifying column, at the point *q*, located below the level at which the pipe *n* enters.

In the main rectifying column *Q*, the plates *r*, in the upper part of the column are cooled by means of a cooling fluid circulating between these plates and the refrigerator *s* and pipes *s*¹ and *s*², while the lower plates *q*, *q*¹ and *q*², are not cooled. Steam is admitted into the main rectifying column *Q* through valve *z*¹ and pipe *z*² and regulated by the differential regulator *j*¹ receiving pressure through pipes *r*¹ and *r*², and additional steam may be introduced from *o* through the pipe and valve *d*', into the bottom of the column.

The wash from the bottom of the main rectifying column passes through pipe *a*⁴ into the preheater *a*¹ for the preheating of condensates from various other sources which are introduced to the first rectifying column *F* through pipe *a*⁵, at the level *g*. The outlet for said wash is through pipe *a*⁶.

From a point *x*, located near, but not at the top of the main rectifying column *Q*, where the vapors richest in alcohol exist, the vapors are drawn off to a condenser and cooler *y*, and from this the purified alcohol is obtained, ready for shipment.

The other vapors from the top of the main rectifying column pass through pipe *t* to condenser *u*, in which they are condensed, the liquid passing through pipe *u*¹ either to the main rectifying column *Q*, at a point

a short distance above the level x , or through the trap v , pipe w to the level g' of the first rectifier F . In practice I prefer to divide a condensate in the condenser u , 5 and convey a portion of the same to the first rectifier and another portion to the main rectifier.

The lower plates q and q' of the main rectifying column Q are intended for the removal of the alcohol from the condensate obtained in the first rectifier F , and also from the refluxes coming from the upper plates r . There is no necessity of cooling the plates q and q' .

15 The impurities of the tails which are less volatile are in these circumstances retained in the lower portion of the column. The alcoholic degree increases to a maximum under the effect of the condensation produced 20 by each plate r . Finally in the uppermost parts of the column traces of the forerunnings products which may still be present, concentrate under the effect of the redistillations which are produced on these cooling 25 plates r .

If it is desired to treat condensates from 30 distilling columns, generally known in the art as phlegms, connection between the two plate columns c and m is closed, by interposing solid disks at the joints e' and p' . Moreover the steam valves e' and e^2 are closed and the steam valves d' and f' are opened connection with the two differential regulators j and j' being closed, by closing on the 35 one hand the respective valves g^3 and h' , and on the other hand the valves t' and r' . The wine admission valve b' is closed, and valve a^2 is opened. This produces a continuous 40 phlegm rectifier of the usual kind, which is for greater clearness illustrated in Fig. 2 by eliminating the elements of the apparatus made idle as above recited.

If it is desired to treat wine directly the converse operations are effected, namely 45 steam is allowed to pass through the joints e' and p' by removing the solid disks, steam valves e' and e^2 are opened, d' and f' closed, g^3 and h' opened and t' and r' are opened, in order to cause the operation of the differential regulators j and j' , of which the construction and operation will be more fully described hereinafter.

In order to successfully operate, the hourly output for bad tasting products should be 55 the same as for good tasting products, in the two different manners of operating on these condensates or wines. The internal pressure existing at the plate g of the first rectifier F , and at the plate g of the main rectifier Q 60 should be constant. This condition will be obtained by forming upon these plates, the respective pressure outlets for the two steam regulators d and o . While these two steam regulators would be sufficient for treating 65 column condensates or phlegms only, since

there is only one heating to control, namely for the first rectifier or the main rectifier, the same does not apply when treating wines, because then each apparatus includes two supplies of heating steam. The regulators d 70 and o control the steam admission at the bottoms of columns c and m . Another means must be provided for controlling the steam inlet at the bottom of g' and q' , and it must be effected in a manner which will not be dependent upon the continued fluctuations or 75 variations of the operations of regulators d and o . This calls for the addition of two differential regulators j and j' , which are alike, and are more fully illustrated in Figs. 80 3 and 4.

This apparatus comprises two superposed compartments 1 and 2. The lower compartment receives through a pipe 4 the pressure of the base of the apparatus (g^2 for the 85 purifier and q^2 for the rectifier); the upper compartment, instead of communicating with the atmosphere, as do the regulators d and o , communicates through a tube 3 with the plate (g or q respectively), that is to say 90 with the columns at the levels which receive the vinous alcoholic vapors of the columns c and m where the regulators d and o tap the pressure for their operation.

Between g^2 and g' , (likewise between q^2 95 and q) there is a difference in pressure of 0.30 meters to 0.40 meters (expressed in values of a column of water), due to the mixing of the vapors with the liquid on the successive plates. The necessary difference in 100 pressure between these two levels having been determined once for all, the regulator is set to maintain exactly this difference.

If the pressure increases, for instance, at the plate g , this momentary excess of pressure acts in the upper compartment of j , causes the level of the water to drop and therefore the float falls, thus opening a little more the steam valve p , and reestablishing to its normal point, the difference in pressure between g^2 and g' .

Thus any pressure may be obtained for the operation of columns c and m without any attention to the heating of g^2 and q^2 being required. They are automatically controlled by the differential regulator which maintains the difference in pressure between g^2 and g' and between g^2 and q constant. 115

In this regulator, the two compartments 1 and 2, instead of being superposed, may be 120 side by side.

Almost all wine distilling columns effect a certain concentration of their alcoholic distillates. It rarely occurs that condensates are produced below 60° C., and sometimes 125 even 90° – 92° C. are attained. This concentration results in an appreciable decrease of the bad odor of the condensate, discharging the most acrid and less volatile products, into the distiller's wash.

In wine rectifiers of the kind shown in Figs. 1 and 1^a, it has been endeavored not to produce, at the top of the exhausting column *m*, any species of alcoholic condensate return, for the following reasons:—

1. To render the exhaustion more easy and less expensive in steam.

2. To prevent the formation of malodorous ethers by the combinations of the acids of the wine with alcohol, a phenomenon which is the more pronounced the greater the alcoholic strength of the wine.

The wine leaving the purifier or preliminary distilling column *c* is boiling and is poorer by that quantity of alcoholic vapor which has passed to the purifier *f g* and has not reentered the wine but has been conducted through *n* to the rectifier.

The vapors which are liberated at the top of *m* are therefore relatively poor in alcohol, and consequently rich in wash odors.

The compound rectifier for wines and condensates which is shown in Figs. 1 and 1^a, is particularly suitable for the continuous rectification of the methyl alcohol which is so difficult to purify.

The apparatus is also applicable to all difficult separations of bodies which boil at different temperatures, and are miscible in all proportions, for instance, for the rectification of acetonated products of forerunning, for the separation of sulfuric ether and alcohol, etc.

The purity of the alcohol depends above all, upon the efficiency of the plates and, from this point of view, there is nothing more efficient than cooled athermanous plates.

For treating wines, the apparatus operates well as a direct rectifier; the vapor liberated by the wine permits of the complete utilization of its heat units in order to boil the liquid on the upper concentrating and rectifying plates; in the majority of the apparatus actually in use, the alcoholic vapor of the wine is condensed with a total loss of heat units and is treated in the subsequent elements as liquid.

What I claim is:—

1. A process for continuously producing concentrated alcohol from fermented alcoholic liquids which comprises heating the liquid sufficiently to drive off the first runnings as vapors and rectifying said first runnings by fractional condensation, heating the liquid from which the first runnings have been removed sufficiently to vaporize all the alcohol contained therein, rectifying the alcoholic vapors thus produced together with the alcoholic condensate from the rectification of the vaporized first runnings, and withdrawing separately the alcohol condensate from the rectification of the combined alcoholic vapors.

*2. A process of continuously obtaining alcohol from a fermented liquid containing

the same which comprises preliminarily heating the liquid, again heating the liquid to a temperature insufficient to vaporize more than a small portion of the alcohol contained therein, withdrawing together the vapors generated in said two heatings, fractionally condensing said vapors by cooling and re-heating and re-condensing the heavier condensates therefrom, exhausting the liquid thus deprived of its lighter vapors by heating the same, fractionally condensing the vapors produced by said heating by cooling, re-heating and fractionally condensing therewith the heavier condensate therefrom and re-heating and fractionally condensing the condensate from the first-mentioned fractional condensation, withdrawing the combined alcoholic vapors from the last-mentioned condensation, withdrawing the uncondensed vapors, condensing the same and returning at least a portion of the condensate for re-heating and condensation to extract the alcohol contained therein.

3. An apparatus for distilling fermented alcoholic liquids comprising a preheater for said liquid, means for distilling off vapors lighter than alcohol from said liquid, a rectifier for rectifying the vapors thus produced and separating alcoholic vapors therefrom, means for distilling off alcoholic vapors from the liquid from which lighter vapors have been removed, and rectifying means for rectifying together said alcoholic vapors and the alcoholic condensate from the first distillation, and means for independently removing the alcoholic condensate therefrom.

4. An apparatus for distilling fermented musts and the like, comprising a preheater for the liquid, a preliminary distilling column, means for conducting liquid from the preheater to the upper part of said column, an inlet for conducting heating fluid to the bottom of said column, a first rectifier comprising cooled plates in the upper portion thereof and plates in the lower portion thereof, means for admitting vapors from said preliminary distilling column to an intermediate point in said first rectifier and for admitting a heating fluid to the lower portion of said first rectifier, an exhausting column and connections for delivering the liquid effluent from said preliminary distilling column to the upper portion of said exhausting column, and means for delivering a heating fluid to the lower end of said main rectifying column, connections for delivering the condensate from the first rectifier to an intermediate portion of the main rectifying column, of which the plates in the upper portion are cooled, means for delivering a heating fluid to the lower end of said main rectifying column, connections for delivering the condensate from the first rectifier to an intermediate portion of the main rectifying column, at a point above the bottom of the cooled plates, connections for introduc-

ing the vapors from the exhausting column to the main rectifying column, at an intermediate level thereof, but below the level at which said condensate is introduced, means 5 for withdrawing alcoholic vapors from a point near the upper end of said column, and for condensing the same.

5. An apparatus for continuously distilling alcohol from liquids and for rectifying 10 the same, which comprises a pre-heater, a preliminary distilling column, means for conducting the liquid from the pre-heater to the upper part of said column, and means for introducing a heating liquid to the lower 15 part thereof, a first rectifier, cooling means associated with the upper portion of said rectifier, and heating means associated with the lower portion thereof, means for withdrawing vapors from the upper part of said 20 column and introducing them into an intermediate portion of said rectifier, an exhausting distilling column, and means for conveying the liquid from said preliminary distilling column to the exhausting distilling 25 column, a main rectifying column, means for cooling the upper portions of said main rectifying column, and means for heating the lower portion of said rectifying column, means for introducing the vapors from said 30 exhausting column to an intermediate portion of said main rectifying column, means for introducing the liquid from said preliminary rectifying column to a level in said main rectifying column above that at which 35 the vapors from said exhausting distilling column are introduced, an alcohol condenser, and means for conducting alcohol vapors from the upper portion of said main rectifying column thereto, a separate condenser, and means for conducting vapors 40 from the top of said main rectifying column to said separate condenser, and means for re-introducing the condensate therefrom at a level above that at which the alcohol 45 vapors are withdrawn.

6. An apparatus for continuously distilling fermented alcoholic liquids comprising means for removing the first runnings of head vapors from said liquids and means for 50 fractionally condensing alcoholic vapors from said first runnings, means for heating the liquid from which the first runnings have been removed to remove the alcohol therefrom as vapor, means for rectifying together the alcoholic condensate from the 55 first runnings and the last mentioned alcoholic vapors, and means for removing separately the rectified alcohol.

7. In an apparatus for continuously producing alcohol from fermented liquids, a 60 distilling column, a rectifying column provided at its lower portion with heating means and at its upper portion with cooling means, a conduit for leading vapors from 65 said distilling column to the rectifying col-

umn at a point below the cooling means, and means for regulating the difference in pressure within said rectifying column between the heating point and the point of admission of said vapors.

8. An apparatus for continuously distilling fermented alcoholic liquids comprising a preheater for said liquids, a distilling column for distilling off vapors lighter than alcohol from said liquid, means for introducing steam into said distilling column, a rectifying column provided at its lower portion with means for introducing steam to heat the same, a conduit for leading vapors from said distilling column into the rectifying column at a point above the point of introducing steam and regulators controlled by the pressure at said point of introduction of vapors for determining the admission of steam to said distilling column and said rectifying column respectively.

9. An apparatus for continuously distilling fermented alcoholic liquids comprising a preheater for said liquid, a distilling column for distilling off vapors lighter than alcohol from said liquid, a rectifier for rectifying the vapors thus produced and separating alcoholic vapors therefrom, a second distilling column for distilling off alcoholic vapors from the liquid from which lighter vapors have been removed, means for introducing steam into the lower portion thereof for heating the same, and a final rectifying column for rectifying together said alcoholic vapors and the alcoholic condensate from the first distilling column, said final rectifying column being provided with means for introducing said alcoholic vapors at intermediate points thereof, means for introducing steam into said final rectifying column at a lower point in said column, and regulators controlled by the pressure at intermediate points of said final rectifying column for determining the admission of heating steam to the second distilling column 105 and the final rectifying column respectively.

10. An apparatus for distilling fermented alcoholic liquids comprising a preliminary distilling column for distilling off vapors lighter than alcohol from said liquid, a rectifier for rectifying the vapors thus produced and separating alcoholic vapors therefrom by condensation, a conduit being provided between said distilling column and said rectifying column for conducting the vapors to the latter, a second distilling column for distilling off alcoholic vapors from the liquid from which the lighter vapors have been removed, a final rectifying column for rectifying together said alcoholic vapors and the alcoholic condensate from the first rectifying column, a conduit being provided between the second distilling column and the final rectifying column for the 110 passage of the alcoholic vapors and a fur- 120 125 130

ther conduit between the first rectifying column and the final rectifying column for passage of the alcoholic condensate, and means for closing off the conduits between each distilling column and the corresponding rectifying column, whereby the distilling columns are completely segregated from the system.

11. An apparatus for distilling fermented 10 alcoholic liquids comprising a preliminary distilling column for distilling off vapors lighter than alcohol from said liquid, a rectifier for rectifying the vapors thus produced and separating alcoholic vapors 15 therefrom by condensation, a conduit being provided between said distilling column and said rectifying column for conducting the vapors to the latter, a second distilling column for distilling off alcoholic vapors from 20 the liquid from which the lighter vapors have been removed, a final rectifying column for rectifying together said alcoholic vapors and the alcoholic condensate from the first rectifying column, a conduit being 25 provided between the second distilling column and the final rectifying column for the passage of the alcoholic vapors and a further conduit between the first rectifying

column and the final rectifying column for 30 passage of the alcoholic condensate, means for closing off the conduits between each 35 distilling column and the corresponding rectifying column, whereby the distilling columns are completely segregated from the system, pipes for supplying steam to each 40 of said distilling columns and rectifying columns, differential regulators operated by variations in pressure between different points in the rectifying columns to control the supply of steam to the rectifying columns, regulators, each controlled by the pressure at a point in one of the rectifying columns, to control the supply of steam to the distilling columns, and means for cutting out the differential regulators from the 45 system and causing the other regulators to control the steam supply to the rectifying columns when the distilling columns are segregated from the system.

In testimony whereof I affix my signature 50 in presence of two witnesses.

EMILE AUGUSTIN BARBET.
